UNITED STATES PATENT OFFICE.

CLEMENT ENGEL, OF NEW YORK, N. Y.

PLANETARY AMUSEMENT APPARATUS.

1,194,158.

Specification of Letters Patent.

Patented Aug. 8, 1916.

Application filed October 14, 1915. Serial No. 55,803.

To all whom it may concern:

Be it known that I, CLEMENT ENGEL, a citizen of the United States, and a resident of the city of New York, borough of Manhattan, in the county and State of New York, have invented a new and Improved Planetary Amusement Apparatus, of which the following is a full, clear, and exact description.

10 The object of the invention is to provide a new and improved planetary amusement apparatus more especially designed as an educational medium to familiarize the user with the planets and their movements 15 around the sun together with their relative sizes and the forces that hold the same in space.

In order to produce the desired result, use 20 is made of a support, on which is centrally located a representation of the sun, carriers 25 adapted to travel around the said representation in concentric circles and planet-indicating members mounted on the said carriers.

25 A practical embodiment of the invention is represented in the accompanying drawings forming a part of this specification, in which similar characters of reference indicate corresponding parts in all the views.

30 Figure 1 is a plan view of the planetary amusement device which may be in the form of a small toy or built on a large scale at amusement resorts with a view to provide interesting rides for the users; Fig. 2 is a 35 sectional side elevation of the same on the line 2—2 of Fig. 1; Fig. 3 is an enlarged sectional elevation of one of the tracks with one of the carriers in position thereon and in the form of a car on which is mounted a 40 planet-indicating member in the form of a merry-go-round; Fig. 4 is a side elevation of a car on an enlarged scale, having means for propelling it and means for rotating the body thereof from one of the wheels.

45 The amusement apparatus illustrated in the drawing is mounted on a platform or other suitable support 10 on which is centrally located a representation of the sun 11, in the form of a huge lamp adapted to be 50 illuminated during the night. On the support 10 are arranged annular tracks 12 concentric relatively to the representation of the sun 11 and representing the orbits of the planets in proportionate relation to the sun 55 and to each other. On the tracks 12 are mounted to travel cars, on the trucks 13 of

which are mounted revoluble bodies 14 in the form of a merry-go-round and in imitation of the corresponding planets. Thus the body 14 for the planet Jupiter is shown 60 with its four largest moons (see Fig. 1) while the body 14 for the planet Saturn is shown with a ball and ring. A bridge 15 is mounted on the support 10 and extends from one side thereof to the representation 65 of the sun 11, and steps 16 lead to the bridge from the outside and steps 17 lead from the inner end of the bridge down to the support 10. From the bridge 15 lead steps 18 to the spaces or platforms between adjacent 70 tracks so that a person can pass down the steps and mount the adjacent body 14 to be carried around on the truck 13 and to be carried with the truck around the corresponding track 12. Motive power is provided 75 for rotating the bodies 14 on the trucks 13 and for propelling the latter along the tracks 12. As shown in Fig. 4 the car is provided with the conventional trolley motor 21 for propelling the same and with 80 means 22 for rotating the body 14 from one of the wheels of the car. It is to be understood, however, that when the apparatus is constructed merely as a toy then such motive power is dispensed with and the trucks 13 85 are propelled by hand and likewise the bodies 14 are turned around on the trucks 13. It is also understood that as the tracks 12 represent the orbits of the planets in 90 their relation to one another and to the representation of the sun, and the trucks 13 with the bodies 14 thereon represent the several planets in relative shape and size, a highly instructive amusement apparatus is provided to familiarize the user with the 95 planets and their movements around the sun. In order to heighten the effect the support 10 is surrounded with a zodiac ring 20 provided at its inner face with the signs of the zodiac visible to the passengers making 100 use of the apparatus.

Having thus described my invention, I claim as new and desire to secure by Letters Patent:

1. A planetary amusement apparatus, 105 comprising a support, a representation of the sun located centrally on the said support, spaced annular tracks on the said support in concentric relation to the said representation of the sun, the tracks representing 110 the orbits of the planets around the sun, cars mounted to travel on the said tracks,

and planet-indicating members revolubly mounted on the cars and representing the several planets.

2. A planetary amusement apparatus, comprising a support, a representation of the same located centrally on the said support, spaced annular tracks on the said support in concentric relation to the said representation of the sun, the tracks representing the orbits of the planets around the sun, cars mounted to travel on the said tracks, planet-indicating members revolubly mounted on the cars and representing the several planets, a bridge on the said support and extending across the tracks from one side of the support to the said central representation of the sun, and steps leading from the bridge to the support between adjacent tracks.
- 20 3. A planetary amusement apparatus, comprising a support, a representation of the sun located centrally on the said support, spaced annular tracks on the said support in concentric relation to the said representation of the sun, the tracks representing the orbits of the planets around the sun, cars

mounted to travel on the said tracks, planet-indicating members revolubly mounted on the cars and representing the several planets, and a zodiac ring around the said support and provided at its inner surface with the signs of the zodiac.

4. A planetary amusement apparatus, consisting of a support provided with a marginal wall having the signs of the zodiac 35 on its inner face and representing a zodiac ring, a lamp at the center of the support and representing the sun, spaced annular tracks on the support in concentric relation to the representation of the sun and representing the orbits of the planets around the sun, and cars mounted on the tracks and having revoluble bodies representing the several planets.

In testimony whereof I have signed my 45 name to this specification in the presence of two subscribing witnesses.

CLEMENT ENGEL.
